UNITED STATES PATENT OFFICE.

FREDERICK B. TOWNSEND, OF CHICAGO, ILLINOIS, ASSIGNOR TO W. H. MINER COMPANY, OF CHICAGO, ILLINOIS, A CORPORATION OF ILLINOIS.

DOUBLE-SPRING FRICTION DRAFT-RIGGING.

SPECIFICATION forming part of Letters Patent No. 761,795, dated June 7, 1904.

Application filed February 24, 1904. Serial No. 195,040. (No model.)

To all whom it may concern:

Be it known that I, FREDERICK B. TOWNSEND, a citizen of the United States, residing in Chicago, in the county of Cook and State of Illinois, have invented a new and useful Improvement 5 in Double-Spring Friction Draft-Rigging, of which the following is a specification.

My invention relates to friction - spring draft-rigging for railway-cars.

10 The object of my invention is to provide a friction draft-rigging of a strong, simple, efficient, and durable construction, composed of few parts and having a very powerful direct-acting spring resistance in connection with a frictional resistance without unduly increasing the length of the draft-rigging as a whole or improperly increasing the longitudinal movement of the draw-bar itself.

My invention consists in the means I employ 20 to practically accomplish this object or result—that is to say, it consists, in connection with a draw-bar and draw-bar yoke or extension secured thereto, a pair of side plates or stop-castings secured to the center sills or framework of the car, and a pair of followers fitting between the upper and lower limbs of the draw-bar extension or yoke, of a longitudinally-sliding laterally-oblong friction-shell having a closed rear end abutting against the

25 rear follower and adapted to be alternately moved with the draw-bar by one follower and held stationary by the other follower, two parallel longitudinally-arranged springs fitting side by side within said laterally-oblong friction-shell, a pair of oppositely-disposed laterally-oblong wedges, one bearing against the front follower and the other against the two parallel springs, a pair of wide laterally-oblong longitudinally-sliding friction-blocks having

30 exterior friction-faces bearing against the upper and lower wide interior friction-faces of said friction-shell, and a pair of longitudinally-sliding narrow friction-blocks having upright exterior friction-faces in sliding frictional engagement with the narrow upright interior friction-faces of said longitudinally-slid-

ing friction-shell. The laterally-oblong longitudinally-sliding friction-shell, by reason of its laterally-extended flat bearing against the follower at its rear end and the coöperative action 50 of the friction-blocks, wedges, and follower at its opposite end, operates to equalize any difference of tension and resistance in the two parallel springs, and thus to prevent any improper tilting of the draw-bar or diagonal 55 or twisting strain on the draft-rigging.

My invention also consists in the novel construction of parts and devices and in the novel combinations of parts and devices herein shown or described.

In the accompanying drawings, which form a part of this specification, Figure 1 is a central vertical longitudinal section of a friction draft-rigging embodying my invention. Fig. 2 is a plan view, partly in horizontal section, 65 on line 2 2 of Fig. 1. Fig. 3 is a cross-section on line 3 3 of Fig. 2. Fig. 4 is a detail perspective view of one of the two wide longitudinally-sliding friction-blocks. Fig. 5 is a cross-section on line 5 5 of Fig. 2. Fig. 6 is a 70 detail elevation, and Fig. 7 is a detail front view, of one of the wedges.

In the drawings, A A represent center sills or longitudinal frame - pieces of the car, A' the cross-sill, and A² the carry-iron.

B is the coupler, B' the draw-bar, and B² the draw-bar extension or yoke rigidly secured to the draw-bar by the bolts or rivets b and interengaging shoulders b' b².

C C' are the followers, and D D are the side 80 plates or stop-castings, each having a front stop d and a rear stop d' to engage the followers and hold the same alternately stationary. The side plates are secured to the sills A A by bolts or rivets d². The sills A are 85 represented as being of an ordinary steel car-frame construction. The side plates or stop-castings D have each an integral upper guide or flange d³ for the followers and also a lower removable guide d⁴, secured thereto by bolts 90 d⁶, having threaded nuts d⁶.

E E are a pair of parallel longitudinally-ar-

ranged springs, the same preferably having small springs $c\ c$ inside the same.

F is a longitudinally-sliding laterally-oblong friction shell or case having a closed rear end f abutting directly against the rear follower C' and fitting between the upper and lower limbs or members of the draw-bar extension or yoke B². The sliding friction-shell F has an externally-projecting rim f' , furnished with a notch or recess f'' to receive the upper limb or member of the draw-bar yoke B², and thus cause the yoke itself to center or guide the friction-shell or hold the yoke and shell centrally in relation to each other. The parallel side-by-side springs E e and E e fit inside the laterally-oblong friction-shell and at their rear ends bear directly against the closed end f of the shell. The laterally-oblong friction-shell F has at its front end or portion two wide horizontal interior friction-faces f^3 and two narrow upright friction-faces f^4 , all of the friction-faces being in planes parallel to the line of draft. The friction-faces f^3 f^4 preferably have inserted wearing-plates f^5 , so that they can be replaced or removed when worn and so that the wearing-faces may be of a different material, if desired, from the friction-faces of the sliding friction-blocks H H'. Inside the laterally-oblong sliding friction-shell F there are two laterally-oblong sliding friction-blocks H H', having exterior horizontal friction-faces $h\ h$ in sliding frictional engagement with the corresponding horizontal friction-faces f^3 of the shell F, and two narrow longitudinally-sliding friction-blocks H' H', having exterior upright friction-faces $h'\ h'$ in sliding frictional engagement with the corresponding upright interior friction-faces f^4 f^4 of the friction-shell F. Each of the sliding friction-blocks H H' has at each end thereof an inclined or wedging face h^2 , contacting with the corresponding inclined or wedging faces g of the two oppositely-disposed laterally-oblong wedges G G'. Each of the wedges G G' has four inclined or wedging faces g , one for each of the friction-blocks H H'. The rear laterally-oblong wedge G' bears against the front ends of the two parallel springs E E, and the front laterally-oblong wedge G bears against the front follower C, being interposed between said follower and the friction-blocks H H'.

In buffing the front follower and the wedges G G' and friction-blocks H H' move with the draw-bar, while the rear follower and friction-shell F are held stationary by the rear stops of the side plates or stop-castings E. In pulling the action is the reverse, the rear follower and friction-shell F moving with the draw-bar and the front follower, wedges, and friction-blocks being held stationary by the front stops on the side plates or stop-castings.

I claim—

1. In a friction draft-rigging the combina-

tion with a draw-bar and draw-bar extension 65 or yoke, of side plates or stop-castings, two parallel longitudinally-arranged springs, a laterally-oblong, longitudinally-sliding friction-shell having two wide and two narrow interior friction-faces, two laterally-oblong and 70 two narrow longitudinally-sliding friction-blocks having exterior friction-faces in sliding frictional engagement with the interior friction-faces of said shell, and furnished each with an inclined or wedging face at each end 75 thereof, and a pair of oppositely-disposed laterally-oblong wedges, substantially as specified.

2. In a friction draft-rigging the combination with a draw-bar and draw-bar extension 80 or yoke, of side plates or stop-castings, two parallel, longitudinally-arranged springs, a laterally-oblong, longitudinally-sliding friction-shell having two wide and two narrow interior friction-faces, two laterally-oblong and 85 two narrow longitudinally-sliding friction-blocks having exterior friction-faces in sliding frictional engagement with the interior friction-faces of said shell, and furnished each with an inclined or wedging face at each end 90 thereof, and a pair of oppositely-disposed oblong wedges, said friction-shell having an external recess or notch to receive one limb of the draw-bar extension or yoke, to cause the laterally-oblong friction-shell to be maintained 95 centrally of the draw-bar extension, substantially as specified.

3. In a friction draft-rigging the combination with a draw-bar, draw-bar extension, side plates and followers, of a laterally-oblong, longitudinally-sliding friction-shell, longitudinally-sliding friction-blocks inside the shell, a pair of longitudinally-extending springs arranged side by side within said shell, and a wedge for causing said friction-blocks to be 100 forcibly pressed and held in sliding frictional engagement with said shell, substantially as specified.

4. In a friction draft-rigging, the combination with a draw-bar and draw-bar extension 110 or yoke, of side plates or stop-castings, two parallel longitudinally-arranged springs, a laterally-oblong, longitudinally-sliding friction-shell having two wide and two narrow interior friction-faces, two laterally-oblong and 115 two narrow longitudinally-sliding friction-blocks having exterior friction-faces in sliding frictional engagement with the interior friction-faces of said shell, and furnished each with an inclined or wedging face at each end thereof, and a pair of oppositely-disposed, laterally-oblong wedges, said friction-shell having a closed rear end against which one end of the springs bear, substantially as specified.

5. In a friction draft-rigging the combination with a draw-bar, draw-bar extension, side plates and followers, of a laterally-oblong longitudinally-sliding friction-shell having one

closed end bearing against one of the followers and against which one end of the two springs bear, longitudinally-sliding friction-blocks inside the shell, a pair of longitudinally-extending springs arranged side by side within said shell, and a wedge for causing said friction-blocks to be forcibly pressed and held

in sliding frictional engagement with said shell, substantially as specified.
